UNITED STATES PATENT OFFICE

105,696

DESIGN FOR A DRESS

Rose Feintuck, New York, N. Y.

Application July 14, 1937, Serial No. 70,405

Term of patent 3½ years

To all whom it may concern:

Be it known that I, Rose Feintuck, a citizen of the United States of America, residing in Manhattan, county of New York, and State of New York, have invented a new, original, and ornamental Design for a Dress, of which the following is a specification, reference being had to the accompanying drawing, forming part thereof, wherein,

The characteristic feature of my design resides in the puffed and Shirred trimming on the sleeves and skirt portions of the dress, as shown.

I claim:

The ornamental design for a dress, substantially as shown, and described.

ROSE FEINTUCK.
